UNITED STATES PATENT OFFICE.

ISRAEL BENJAMINS, OF NEW YORK, N. Y.

STEAM-BOILER OR FLUID-HEATER.

1,029,908.

Specification of Letters Patent. Patented June 18, 1912.

Application filed July 18, 1911. Serial No. 639,254.

To all whom it may concern:

Be it known that I, ISRAEL BENJAMINS, a citizen of the United States, residing at 22 Lewis street, in the city of New York, county of New York, and State of New York, have invented a new and useful Steam-Boiler or Fluid-Heater, of which the following is a specification.

My invention relates to improvements in fluid heating apparatuses in which one fluid is employed to transmit the heat it contains or part of the heat it contains to another fluid simultaneously receiving the said heat, such as boilers, air heaters, feed water heaters, economizers, condensers, and other apparatuses for sundry special manufacturing purposes; but particularly to boilers used for generating steam of either high or low pressure and for water heating purposes.

The objects of my improvement are to produce a type of a boiler or fluid heater which is less expensive, more efficient and more compact than the standard types of boilers and fluid heaters of current practice, also to produce a type of a boiler which is safer than the existing types of boilers, and particularly a boiler which should be about as efficient when built in small sizes as in large sizes, and of which the efficiency should be more or less independent of the skill of the fireman; the boiler should at the same time be of comparatively simple construction so as to necessitate no expensive special machines for its manufacture, and to have its parts easily accessible for cleaning and inspection. I attain these objects by the apparatus hereinafter described and illustrated in the accompanying drawings which represent one convenient form of my invention, which is generic in character and which admits of many modifications of shape embodying either all or some of the features of my invention, as is hereinafter more fully pointed out.

In the drawings, Figure 1 represents a vertical section through one type of the boiler, with the ash pit omitted, but showing the grate in position, also a part of the stack, (or flue leading to the stack): Fig. 2 is a plan or top view of one type of the boiler, in which the drawing to the right of

the center line A A is a view taken with all the parts of the boiler assembled, the drawing in the upper left hand quadrant 55 is a view taken with the uppermost section 18 removed: the drawing in the lower left hand quadrant of Fig. 2 is a view of the section 1 of the boiler with the upper sections 15 and 18 removed. Fig. 3 is a plan 60 or top view of a type of the boiler which is elongated in shape and which is particularly adapted to locomotives and for large stationary and marine plants.

Wherever in this specification the term 65 "heat absorbing surface" is employed it designates the surface in contact with the heating fluid, and the term "heat emitting surface" designates the surface in contact with the heated fluid; similarly the terms 70 heat absorbing passages and heat emitting passages mean the passages in contact with the heating and heated fluids respectively.

Similar characters refer to similar parts throughout the several views in the drawings.

1 is the section or sections containing the furnace 2 surrounded by the water spaces 3 and 4 which communicate with each other by means of the passages 5 and 5^a. 80 *

6 is the grate of any usual design; 7 is a deflector or baffle plate or plates shown in Fig. 1, as cast in one with the section or sections 1, and as forming a continuation of the inner wall 33 of the same; but which 85 may also be made separate; 8 is a lining of tiles, fire clay or some other refractory material, and which is designed to protect the combustion of the gases in the furnace 2 from the chilling effect of the inner walls 33, also to protect the baffle 7 from overheating; 15 is the main boiler section or sections containing the large central combustion chamber or flue 10, which receives the gases of combustion after they leave the 95 furnace 2, and the sets of passages 13 which receive the gases of combustion after they leave the flue 10, and after being deflected by the hollow baffle 11 containing the dead air space 12; from the passages 13 the hot 100 gases pass through the smoke deflecting and soot settling chamber or chambers 9, situated between and inclosed by the lower section or sections 1 and the main section

or sections 15, which contains also the passages 14 which receive the hot gases from the chamber or chambers 9, and discharge them into the uptake or uptakes 16 situated 5 between and inclosed by the baffle 11 and the uppermost section or sections 18, which is attached to the section or sections 15, at the inner joints 29, and the outer joints 30; the section or sections 18 is adapted to in- 10 close a steam space 19, between itself and the section or sections 15; 17 is a part of the stack or flue leading to the stack; 20 are the flanges which connect sections 1 and 15, also sections 15 and 18; 21 is a 15 coil or pipe which is connected by means of the fitting 22, to the feed water pipe 23; this coil or pipe 21 is adapted to deliver the feed water through suitable apertures in its walls into the outer passages 36 of the sec- 20 tion or sections 15, through which passages the feed water then descends, partly evap- orating, and delivering the mud and scale, which it contains, if any, into the chambers 4 and 3, and then it rises into the passages 25 24 also contained by the section or sections 15; in which passages 24 most or all of this circulating water evaporates, and the steam there formed together with the water, if any, is delivered into the steam space 19 30 after being deflected by the steam and water baffle 25 which is shown as crown shaped, in Fig. 1, and which is adapted to separate the water from the steam; the passages 24 and 26 with the steam chamber 19 and the mud 35 chambers 4 and 3 and passages 5 and 5^a form the circulating system of the boiler or fluid heater.

26 are two steam connections to the boiler (the gage cocks and their connections to the 40 boiler are not shown).

27 is one of a number of long bolts, with an extra nut 28, shown as connecting the sections 1, 15 and 18 together; the long bolts, by their elongation within the elastic 45 limit are adapted to allow the uppermost section 18 to be lifted from the seat of the inner joint 29 of the sections 15 and 18, while still retaining contact at the outer joint 30 of the same sections, at the circum- 50 ferential sliding part of the said joint 30, and in this way allowing the section 18 of the boiler to act as a safety valve along the joint 29 which has a shorter circumferential sliding contact, and which length of the 55 sliding contact of said joint 29, is adapted to be varied by the insertion of a suitable gasket at the seat of the joint 29, between the ends of the sections 15 and 18 at that joint, and thus allowing the steam to escape 60 at any required pressure into the uptake 19; the extra nuts 28 are designed to prevent the escape of hot water and steam at the joints of the sections 1 and 15.

32 are the flanges of the stack or flue leading to the stack 17; 34 is a blow off connection; 35 is a support for the grate, which support may be of any suitable form. 65

It is evident from the drawings that the passages 13 and 14 of the section or sections 15 could be formed by coring or drilling, and will therefore cost much less than tubes would, and they will be much stronger; the same is true of the passages 24 and 36 in the same section or sections 15, and of the passages 5 and 5^a in the section or sections 1; 70 it is also evident that sections 1, 15 and 18 are adapted to be made by casting them which is less expensive than building up a boiler of plates and tubes as is now the general practice; and that any well equipped foundry and machine shop could produce these boilers without any special machines for bending and flanging boiler plates, etc. 75 It is also evident that this type of a boiler herein disclosed will be immensely stronger 80 than any of the boilers known in current practice as safety boilers, on account of the large mass of metal and the small size of the water spaces which this type contains, also on account of the absence of riveted joint, 85 of sheet metal, and of joints of tubing; the walls of all the passages of my boiler are moreover connected into solid blocks, and the quantity of water contained in this boiler at any time is comparatively small, so that 90 there is scarcely any possibility of any explosion; and no probability of the failure of 95 this type of boiler under any circumstances. The safety of this boiler is still further increased by the feature of enabling the upper 100 section or sections 18 of the boiler itself to act as a safety valve, as above described. It is evident also that with this type of a boiler or fluid heater, the fire surface or heat absorbing surface is distinct from the water 105 surface or heat emitting surface, and that the heat absorbing surface may be made many times as large in area as the heat emitting surface or vice versa; the total heat absorbing surface of the combustion flue 110 and of the passages 13 and 14 being much larger than the heat emitting surface of the 115 passages 24 and 36, as can readily be seen from the drawings. This is designed for the purpose of increasing the capacity of a 120 boiler of a given size, or to reduce the bulk of a boiler of a given capacity. It is also evident that in the case of other fluid heaters, where the transfer of the heat to the heated fluid is the slower process, the area 125 of the heat emitting surface may be designed much larger than the heat absorbing surface. The passages cored or drilled in a block or casting can also be made considerably smaller in size or diameter than boiler tubes which would buckle if too small; the

heating surface could therefore be made considerably larger in this type of a boiler for the same size, or the bulk of the boiler reduced for a given amount of the heating surface of the boiler or fluid heater. It is also evident that the transmission of heat from the extremely hot gases in the combustion chamber or flue 10 to the water and steam in the passages 24 and 36 will be retarded not so much by the thickness of the metal intervening, as by the passages 13 and 14 which reduce the area of the heat transmitting section of the metal, and also, to some extent, by the extra thickness of the metal; hence the temperature of the walls of the combustion chamber or flue 10 will be high, and the said thickness of the metal could be varied in design together with the number and size of the passages 13 and 14, so as to have the temperature of the said walls of the said combustion chamber or flue 10 of any desired intensity; this feature of the design will protect the gases of combustion in the chamber or flue 10 from the chilling effect of the water and steam surface, while transmitting the heat at the same time, and the combustion of the gases will therefore be far more complete in this type of a boiler than is the case in boilers of all current types having water and steam on one side of tubes or plates and the gases of combustion on the other, in which current types of boilers, the combustion is for this reason incomplete, particularly in boilers of the smaller sizes where the action is aggravated by the larger ratio of the said chilling surface to the volume of the gases of combustion. This above described feature of protecting the gases of combustion from chilling while transmitting the heat will not only increase the efficiency of a boiler of this type, but it will also enable small boilers of this type to have the same or nearly the same efficiency as large ones. It is also evident that the completeness of combustion in boilers of this type will be independent of the vigilance of the fireman and without taxing either his time or his attention, and that the efficiency of the boiler will be constant and high as long as the supply of air to the fuel will be kept within proper limits. This increase of efficiency will still further reduce the size of a boiler of a given power, and this reduction of bulk will be particularly telling in boilers of small sizes which as at present designed, are very inefficient, and therefore also very bulky for any given power. It is also evident that this type of a boiler could be run as a semiflash boiler, by restricting the supply of feedwater, or even as a flash boiler, without any injury to the boiler; in this latter case, however, the boiler must be connected to a feed water heater, or hot

well communicating with the steam space of the boiler, into which hot well or feed water heater the water should be pumped or injected at intervals, and from which the water should descend by gravity through a regulating valve into perforated coil 21 feeding the boiler. It is also evident that the extra great strength of this type of a boiler will permit the cleaning of any scale in the steam and water passages 24 and 36 by the heroic method of heating up the boiler dry, and then cooling it down, thereby causing the disintegration of the scale and its removal from the surfaces incrusted with it. It is evident also that on account of the protection of the gases of combustion from chilling, as hereinbefore described, there will be very little soot in boilers of this type, and the repeated baffling and change of direction of the flow of gases will cause the precipitation of whatever soot there will be, and will prevent the carrying of soot and other solid particles of fuel into and through the stack as is the case with locomotive boilers, and with boilers fired with soft coal. The hereinbefore described feature of the protection of the gases of combustion from chilling in this type of a boiler, will also make it possible for soft coal to be burned with a high efficiency and with very little smoke.

The passages 13, 14, 24, and 36 also 5 and 5^a, are shown round in Figs. 2 and 3, for the purpose of facilitating their cleaning; otherwise they may be made of any other suitable form.

The mud-chambers 3 and 4 are provided in duplicate to facilitate the separation of the mud and precipitates by means of the gentler circulation through the openings, 5^a and 5 of the section or sections 1, whereas the circulation through the openings 36 and 24 of the section or sections 15 will necessarily be more rapid and disturbed.

The dead air space 12 is provided in the baffle 11 for the purpose of checking the transmission of heat from the gases in the combustion chamber or flue 10 to the gases in the uptake 16 and in the stack or flue leading to the stack 17; the baffle 11 may also advantageously be lined on its underside with some nonconductor of heat, such as asbestos or fireclay, but which is not shown in the drawings.

The lining of tiles or fireclay 8 of the furnace 2 and baffle 7 is shown as extending beyond the inner joint 31 of the sections 1 and 15, and into the combustion chamber or flue 10, for the purpose of protecting and to prevent the overheating of the thin metal wall separating the flue 10 from the chamber or chambers 9.

The boiler as illustrated in Figs. 1, 2 and

3, is shown vertical; but it is evident that it could be built inclined, or even horizontal with very little change in its design; sections 1, 15 and 18 are shown in the drawings as made each in one block or casting; but it is evident that in the larger sizes any of these sections could be made to consist of a number of smaller sections suitably connected by flanges or otherwise. The number of sections may also be reduced to two and even to one if desired.

Fig. 1 shows the arrangement whereby the gases of combustion change direction twice; but it is evident that the number of turns may be increased and that also by leaving out from the design the passages 14, the gases would change direction only once, and by leaving out the central flue 10 and the passages 14, the gases would not change their direction at all; also when using a detached furnace, the furnace inclosed by section 1 may be omitted. The passages 24 and 36 could also be dispensed with, if desired, and section 15 simply inclosed in a water shell or drum. The design of the section 15 of the boiler thus simplified could be used as part of a larger design taking the place of the fire tube of boilers of present design. It is also evident that the sets of passages 13 and 14 or either of them, containing the gases of combustion could be made to envelop the passages 24 and 36 containing the water and steam; and the central flue 10 could be made to contain water and steam, if desired, instead of serving as a combustion chamber. Similar modifications could be made with fluid heaters other than boilers; also instead of the passages 13, 14, 24, 36, and also 5 and 5* being straight, as shown in Fig. 1, they could be made helical, or having any other fanciful shape. Many other changes could be made in the design of my boiler within the scope of my invention.

The cardinal features of the design of my boiler consist in the passages honeycombed in blocks or castings to form heat absorbing surfaces and heat emitting surfaces or either of these; also in so placing the water and steam passages relative to the combustion chamber that the combustion of the gases is protected from the chilling effect of the water and steam by intervening heat absorbing passages formed in the section or sections enveloping the combustion chamber, or by any similar means; the first of these features applies to fluid heaters in general; the latter feature applies to boilers in particular. All the other features of the boiler hereinbefore described and shown in the drawings, or the modifications of the same, are contributory to the value or advantages of the boiler as hereinbefore described.

What I claim as my invention and desire to secure by Letters Patent is:

65

1. A boiler or fluid heater having multiple passages formed in a block or casting the said passages being adapted to act as heat absorbing surfaces.

2. A boiler or fluid heater having multiple 70 passages formed in a block or casting the said passages being adapted to act as heat emitting surfaces.

3. A boiler or fluid heater consisting of sections secured together and having multiple 75 passages honeycombed in one or more of the said sections, the said passages being adapted to act as heat absorbing surfaces.

4. A boiler or fluid heater consisting of sections secured together, and having multiple 80 passages honeycombed in one or more of the said sections, the said passages being adapted to act as heat emitting surfaces.

5. A boiler or fluid heater consisting of sections secured together, and having a set 85 or sets of passages honeycombed in one or more of the said sections the said set or sets of passages being adapted to act as heat absorbing surfaces, and another set or sets of 90 passages adapted to act as heat emitting surfaces.

6. A boiler or fluid heater consisting of sections secured together, and having a set or sets of passages honeycombed in one or more of the said sections, the said passages 95 being adapted to act as heat absorbing surfaces, and another set or sets of passages adapted to act as heat emitting surfaces, said heat absorbing passages having a considerably larger total area than the said 100 heat emitting passages.

7. A boiler or fluid heater consisting of sections secured together, and having multiple 105 passages honeycombed in one or more of the said sections, combined with a suitable combustion chamber.

8. A boiler or fluid heater consisting of sections secured together, and having multiple 110 passages honeycombed in one or more of the said sections, combined with a suitable steam space or chamber.

9. A boiler or fluid heater consisting of sections secured together and having a set or sets of multiple passages honeycombed in one or more of the said sections, combined 115 with a combustion chamber and a steam and water space or spaces, one or more of the said sets of passages intervening between the said combustion chamber and the said steam and water space or spaces.

10. A boiler or fluid heater consisting of sections secured together, and having a set or sets of heat absorbing passages honeycombed in one or more of the said sections combined with a combustion chamber and a 125 steam and water space or spaces, said set or

sets of heat absorbing passages intervening between said combustion chamber and the said steam and water space or spaces.

11. A boiler or fluid heater consisting of 5 sections secured together, and having a set or sets of heat absorbing passages and a set or sets of heat emitting passages honeycombed in one or more of the said sections combined with a suitable combustion chamber, the said set of heat absorbing passages intervening between the said combustion chamber and the said set of heat emitting passages.

12. A boiler or fluid heater consisting of 15 sections secured together and having multiple passages honeycombed in one or more of the said sections combined with a suitable space or spaces adapted to act as a mud settling chamber or chambers.

20 13. A boiler or fluid heater consisting of sections secured together and having multiple passages honeycombed in one or more of the said sections, combined with suitable mud settling spaces or chambers and circum- 25 lating passages connecting the said mud settling spaces or chambers.

14. A boiler or fluid heater consisting of sections secured together, and having multiple heat emitting passages honeycombed 30 in one or more of the said sections, combined with steam and water spaces or chambers, said heat emitting passages being adapted to form a circulating system with the said steam and water spaces or chambers.

15. A boiler or fluid heater consisting of sections secured together, and having an inner and an outer set of heat emitting 40 passages honeycombed in one or more of the said sections, combined with steam and water spaces or chambers, said sets of heat emitting passages being adapted to form a circulating system with the said steam and water spaces or chambers.

45 16. A boiler or fluid heater consisting of sections secured together and having a set or sets of heat emitting passages honeycombed in one or more of the said sections, combined with steam and water spaces and 50 a perforated coil or pipe, the said heat emitting passages being adapted to form a circulating system with the said steam and water spaces, and the said perforated coil or pipe being adapted to deliver a stream or streams 55 of feed water into the said circulating system.

17. A boiler or fluid heater consisting of sections secured together, and having multiple heat emitting passages honeycombed 60 in one or more of the said sections, combined with steam and water spaces and a steam deflector in the said steam space, said heat emitting passages being adapted to

form a circulating system with the said steam and water spaces, and the said steam 65 deflector being adapted to separate the water from the steam delivered by the said circulating system into the said steam spaces.

18. A boiler or fluid heater consisting of sections secured together, having multiple 70 heat absorbing passages honeycombed in one or more of the said sections, combined with a combustion chamber and a suitable smoke deflector, the said smoke deflector being adapted to deflect the gases of combustion 75 from the said combustion chamber into the said heat absorbing passages.

19. A boiler or fluid heater consisting of sections secured together, and having an inner and an outer set or sets of heat absorbing 80 passages honeycombed in one or more of the said sections, combined with a suitable smoke deflecting and soot settling chamber or chambers, the said chamber or chambers being adapted to deflect the gases 85 of combustion from one of the said sets of heat absorbing passages into the other one of the said sets, and to collect the soot deposited from the said passages.

20. A boiler or fluid heater consisting of 90 sections secured together, and having multiple heat absorbing passages honeycombed in one or more of the said sections combined with a suitable smoke uptake and a suitable smoke flue or stack, the said smoke 95 uptake being adapted to direct the gases of combustion issuing from the said heat absorbing passages into the said smoke flue or stack.

21. A boiler or fluid heater consisting of 100 sections secured together, and having multiple heat absorbing passages honeycombed in one or more of the said sections, combined with a suitable furnace or furnaces, said furnace or furnaces being adapted to 105 produce the gases of combustion in contact with the said heat absorbing surfaces.

22. A boiler or fluid heater consisting of sections secured together, and having multiple heat absorbing passages honeycombed 110 in one or more of the said sections combined with water spaces and a suitable furnace surrounded by the said water spaces, the said furnace being adapted to produce the gases of combustion in contact with the 115 said heat absorbing passages.

23. A boiler or fluid heater consisting of sections secured together and having multiple heat absorbing passages honeycombed 120 in one or more of the said sections, combined with a suitable furnace, a combustion chamber and a suitable flame deflecting plate or plates, the said flame deflecting plate or plates being adapted to direct the gases of combustion from the said furnace 125 into the said combustion chamber.

24. A boiler or fluid heater consisting of sections secured together, and having multiple passages honeycombed in one or more of the said sections, combined with long bolts adapted to allow one or more of the said sections to act as a safety valve.

25. A boiler or fluid heater consisting of sections secured together and having multiple heat absorbing and heat emitting passages honeycombed in one or more of the said sections, combined with a furnace, combustion chamber and uptake and with a steam

chamber and mud settling chamber, the said furnace, combustion chamber and uptake, or some of these being inclosed by the said sections, and the said steam chamber and mud settling chamber being adapted to form a circulating system with the said heat emitting passages. 15
